UNITED STATES PATENT OFFICE.

ALFRED S. DUFFIES, OF MARKESAN, WISCONSIN, AND FRANCIS MEAD, OF CHICAGO,
ILLINOIS.

CUSHIONED WHEEL.

1,307,809.

Specification of Letters Patent. Patented June 24, 1919.

Application filed May 3, 1916. Serial No. 95,111.

To all whom it may concern:

Be it known that we, ALFRED S. DUFFIES, residing at Markesan, in the county of Green Lake and State of Wisconsin, and 5 FRANCIS MEAD, residing at Chicago, in the county of Cook and State of Illinois, both citizens of the United States, have invented certain new and useful Improvements in 10 Cushioned Wheels; and we do hereby declare the following to be a full, clear, and exact description of the invention, such as will enable others skilled in the art to which it appertains to make and use the same.

Our invention relates to resilient or cushioned vehicle wheels and more particularly to the general class of wheels in which inner and outer fellys or rims are separated by cushioning elements disposed in annular formation between the said fellys or rims. 15 In wheels of this class (such as those shown in our co-pending application, filed March 31st, 1916, as Serial No. 87,902, or that shown in United States Patent No. 1,195,379, issued to Francis Mead on Aug. 22, 1916) 20 it has heretofore been customary to employ cushions of rubber or the like projecting laterally beyond the two sides of the inner felly, and to equip the outer felly with an annular side flanges extending alongside these 25 projecting portions of the cushions radially inward from the outer felly. When wheels equipped in this manner are in service, the side strains due to skidding, twisting action when turning corners, and other 30 causes, often cause a relative lateral movement of the inner and outer fellys, thereby placing a considerable strain on the side flanges. In practice, we have found that when the side flanges are supported only by 35 bolts passing through the outer felly of the wheel, this strain comes on laterally unsupported portions of the side flanges. Consequently, such a strain will tend to bend the side flanges out of shape if the latter are 40 made of relatively light material; or, if the flanges are of sufficiently heavy material to resist a strain tending to bend them, this strain will tend to shear off the nuts and heads of the bolts which fasten the flanges 45 to the outer felly.

The general objects of our invention are to overcome these flange-bending and bolt-head-shearing tendencies by providing auxiliary supporting or spacing means radially 50 inward of the outer felly, thereby prevent-

ing a relative lateral movement of the two side flanges and affording the desired rigidity of the latter without resorting to the use of heavy material. More particularly, our invention also aims to provide flange- 60 spacing means which may be used with the constructions shown in the aforesaid co-pending applications without interfering either with the normal action of the cushioning arrangement or the easy assembling 65 of the wheel. Further objects will appear from the following specification and from the accompanying drawings, in which—

Figure 1 is a fragmentary side elevation, partly in section of a vehicle wheel equipped 70 with one embodiment of our invention.

Fig. 2 is a transverse section through the same, taken along the line 2—2 of Fig. 1 and showing spacer means comprising a bolt and a sheath. 75

Fig. 3 is a fragmentary section showing spacer means comprising a rod and two screws.

Fig. 4 similarly shows spacer means comprising a tube and a pair of screws threaded 80 into each other.

Fig. 5 is a fragmentary section showing our invention as applied to a wheel construction of the type disclosed in our co-pending application Serial No. 87902. 85

Fig. 6 is a similar section showing an embodiment of our invention in which the spacer elements pass between the spokes of the wheel.

Fig. 7 is a fragmentary side elevation of 90 the wheel of Fig. 6.

While our invention may be applied to resilient wheels of widely different types, it is particularly adapted to those using rubber cushions arranged in two annular formations between inner and outer rims and separated by a spacing flange carried by one of the rims. For example, in Fig. 1, the inner rim or felly 1 carries a metal band 2 supporting a centrally disposed spacer band 95 3 made of steel of an inverted T-shaped cross-section, which band separates parallel cushions 4 of soft rubber or the like.

These cushions project respectively beyond the opposite sides of the inner rim 1 and into 100 contact with side flanges 5 secured to opposite sides of the outer rim 6 by bolts 7. It will be obvious from Fig. 2 that any relative lateral movement of the outer rim toward the right will carry the left-hand side flange 110

with it and compress the left-hand cushion 4 between this flange and the spacer band 4. Consequently, the resistance of this cushion to the compressing strain will tend to hold 5 back the adjacent portion of the left-hand flange 5, thereby tending both to bend this flange and to shear off the head 8 of the bolt 7. To resist these strains, we connect the opposite side flanges by auxiliary spacer 10 means, such as bolts 9 extending parallel to the axis of the wheel through portions of the side flanges disposed between the two wheel rims, and tubes 10 fitted over these bolts and bearing at both ends against the 15 respective flanges 5. The spacer band 4 is then preferably cut away opposite each of these bolts (as shown in Fig. 1) so as to leave plenty of play for these bolts and tubes during the relative movement of the wheel 20 rims.

If the side flanges extend radially also alongside parts of the inner rim, as in the construction of our aforesaid co-pending patent application, the auxiliary spacer 25 means may pass through perforations 11 in the inner rim, which perforations are preferably considerably larger in diameter than the outside of the spacer means. Thus, in Fig. 5, the main transverse bolts 7 fasten two 30 pairs of superposed side flanges 5^a to the outer rim 6, and waterproofed fabrics 13 are clamped between these flanges both by the said bolts and by screws 14 threaded into rods 15, which screws and rods form the 35 auxiliary spacer means of this embodiment of our invention. Likewise, in Figs. 6 and 7, side flanges 5^b of a single thickness are curved so as to underhang the inner rim or felly 1, and are connected near their radially 40 inner edges by spacer means extending between the spokes 16 and consisting of rods 15 and screws 14.

In every case, it will be obvious that by 45 using spacer means including portions between which the side flanges are clamped (as for example, the bolt head and nut in Fig. 2 and the adjacent ends of the tube 10), we maintain the radially inward portions of the side flanges 5 rigidly spaced, thus preventing 50 a flexing of these flanges and distributing any side strains both through the cushioning elements of the wheel and through

the said spacer means. Consequently, we are able to secure the desired rigidity and strength with much lighter and less clumsy 55 side flanges than those required where such flanges are held only by their connections to the outer rim 12. Moreover, walls of the transverse perforation 16 in the inner felly of Fig. 5 can, if desired, be used as stops for 60 limiting a relative circumferential motion of the inner and outer wheel rims; or, in Fig. 1, the ends 17 of the annular spacer band 3 can coöperate with the spacer tubes 10 for the same purpose. However, we do not wish to 65 be limited to this feature, nor to other details of the constructions herein described, it being evident that our invention may be embodied in many other forms without departing from the spirit of the appended 70 claims. For example, a pair of screws 14 threaded into opposite ends of a rod 15 (as in Fig. 3) may be substituted for the bolt and the sleeve or tube of Fig. 2; or a pair of threadedly connected screws 18 may replace the single bolt 9, as in Fig. 4.

We claim as our invention:

1. A vehicle wheel including the combination with inner and outer rims and cushioning means interposed therebetween of side 80 flanges secured to one of the rims and contacting with the sides of the cushioning means, said flanges being spaced from the other rim to permit relative lateral movement of the rims, and spacing members rigidly connecting opposed portions of the flanges whereby to distribute through both flanges lateral stress applied to either flange.

2. A vehicle wheel including the combination with inner and outer rims and cushioning means interposed therebetween of side flanges secured to one of the rims and contacting with the sides of the cushioning means, and members extending transversely through the cushioning means for rigidly 95 connecting said flanges to distribute lateral stresses therein, said spacing members continuously contacting with the cushioning means to apply load stress thereto at portions adjacent said spacing members.

Signed,

ALFRED S. DUFFIES.
FRANCIS MEAD.
